UNITED STATES PATENT OFFICE.

JOHN FERREOL MONNOT AND EDWARD TINDALL COOK, OF LONDON, ENGLAND.

AUDIBLE SIGNAL DEVICE OF THE VIBRATORY-DIAPHRAGM TYPE.

Application filed June 24, 1919. Serial No. 306,454.

To all whom it may concern:

Be it known that we, JOHN FERREOL MONNOT and EDWARD TINDALL COOK, both subjects of the King of Great Britain, residing, respectively, at 1 King Street, St. James, and 38 Blandford Street, both in the county of London, England, have invented certain new and useful Improvements in or Relating to Audible Signal Devices of the Vibratory-Diaphragm Type, of which the following is a specification.

This invention relates to audible signal devices of the kind in which a diaphragm is vibrated by means of an electrically operated rotor provided with teeth or projections, the chief object being to construct such signal devices whereby they can be utilized more particularly in connection with aircraft for the purpose of giving signals on the Morse or other code in a more efficient manner than heretofore.

According to this invention the signal device is provided with means whereby the diaphragm is normally maintained in a buckled condition out of contact with the rotor and permitted to assume a condition in which it will make contact therewith only when it is desired to give a signal. The said means may comprise a pivoted lever so arranged as to be capable of buckling the diaphragm out of contact with the rotor and maintaining it in this condition until the desired signal is to be given whereupon the said lever is actuated manually, electrically or otherwise in order to permit the diaphragm to make contact with the rotor which is caused to revolve continuously at a predetermined speed by mechanical or electrical means said speed being kept constant by providing the rotor with a fly wheel. This arrangement enables loud and distinct notes of the desired duration to be obtained on the Morse or other code with the consumption of the minimum amount of energy that is to say the motor need only be a small one possessing no more power than that necessary to continuously drive the fly wheel, which latter stores up energy during the periods of light load, when the diaphragm is not being vibrated, which is available when the heavier loads arise due to the vibration of the diaphragm in signalling, thus ensuring that the said notes shall not vary in pitch as would occur in the absence of the fly wheel by the slowing down in speed of the continuously running rotor

when the extra amount of work involved in vibrating the diaphragm were imposed upon it. Moreover as the diaphragm alone requires to be moved relatively to the rotor each time a note is to be sounded the actuating parts need only be light in construction or of small mass so that they can be moved much more quickly than would be the case if the rotor had to be moved relatively to the diaphragm or the horn together with the diaphragm had to be moved relatively to the rotor, consequently rapid code signalling can be effected.

In order that the said invention may be clearly understood and readily carried into effect, the same will now be described more fully with reference to the accompanying drawing, in which:—

Figure 1 is a vertical section and

Figure 2 a fragmental sectional plan view of a signal device embodying the invention, the rotor being adapted to be driven by means of an electric motor.

a denotes the rotor, *b* the vibratory diaphragm and *c* the lever for effecting the buckling of the said diaphragm, which is shown interposed between a sound-amplifying horn *d* and a casing *e* within which the rotor is adapted to revolve at a constant predetermined speed through the medium of a shaft *f* operated by a continuously running electric motor *g* the casing of which is connected by means of an upright sleeve bearing *h* to the rotor casing *e*. *i* denotes the fly wheel for maintaining the speed of the rotor constant during the vibration of the diaphragm, the said fly wheel being shown secured to the shaft *f* and arranged within the motor casing contiguous to the armature *j*. The said lever *c* is pivotally mounted within the casing *e* which is provided with a slot or opening (not shown) through which the outer end of the lever passes, the said lever being operated in any appropriate manner whereby the inner end thereof can effect the buckling of the diaphragm *b*, as shown in full lines in Figures 1 and 2, and thus maintain the button *k* thereon normally out of the path of movement of the teeth on the rotor which is adapted to be revolved continuously at a uniform rate of speed, as aforesaid, or whereby the diaphragm can be permitted to assume a position in which the said button lies in the path of movement of the rotor as shown in dotted lines in Figures 1 and 2,

when it is desired to give a signal. In the example shown, the buckling of the diaphragm is effected through the medium of a spring *l* acting upon the lever *c* and the means for enabling the diaphragm to occupy the position shown in dotted lines so that the button thereof can make contact with the teeth of the rotor, comprise a pin *m* which is provided with a head *n* whereby the 10 said pin can be operated by hand and actuate the lever *c* against the action of the spring *l*. The said pin *m* may also constitute the core of an electromagnet *p* arranged in an electric circuit (Figure 2) 15 adapted to be opened and closed by a switch *q*, the closing of the circuit causing the pin *m* to operate upon the lever *c* and enable a signal to be given, the duration of the sound produced being dependent on the length of 20 time which the pin *m* is maintained in engagement with the lever *c*. Stops *r* serve to limit the movement of the said lever.

What we claim and desire to secure by Letters Patent of the United States is:—

25 1. An audible code signalling device consisting in the combination of a vibratory sound emitting diaphragm, a rotor adapted to vibrate said diaphragm, a motor for driving said rotor continuously at a predetermined speed, means engaging with the periphery of said diaphragm and supporting it at a fixed distance from said rotor, means for deflecting the central portion of said diaphragm out of contact with said rotor 30 and for permitting it to make contact therewith only when a signal is to be sounded, and means whereby the predetermined speed of the continuously driven rotor is maintained unchanged when the diaphragm 35 makes contact therewith so that a sound of constant pitch will be emitted at each signal.

2. An audible code signalling device consisting in the combination of a vibratory sound emitting diaphragm, a rotor adapted to vibrate said diaphragm, a motor for driving said rotor continuously at a predetermined speed, means engaging with the periphery of said diaphragm and supporting it at a fixed distance from said rotor, means for deflecting the central portion of said diaphragm out of contact with said rotor and for permitting it to make contact therewith only when a signal is to be sounded, 55 and a fly wheel driven by said motor for maintaining unchanged the predetermined speed of the continuously driven rotor when the diaphragm makes contact therewith so that a sound of constant pitch will be emitted at each signal.

3. An audible code signalling device consisting in the combination of a vibratory sound emitting diaphragm, a rotor adapted to vibrate said diaphragm, a motor for driving said rotor continuously at a predetermined speed,

mined speed, means engaging with the periphery of said diaphragm and supporting it at a fixed distance from said rotor, mechanical means whereby the diaphragm is normally maintained in a buckled condition 70 out of contact with said rotor, means whereby said diaphragm buckling means can be actuated for permitting the diaphragm to assume a condition in which it will make contact with the rotor to sound a signal, 75 and means whereby the predetermined speed of the continuously driven rotor is maintained unchanged when the diaphragm makes contact therewith so that a sound of constant pitch will be emitted at each signal. 80

4. An audible code signalling device consisting in the combination of a vibratory sound emitting diaphragm, a rotor adapted to vibrate said diaphragm, a motor for driving said rotor continuously at a predetermined speed, means engaging with the periphery of said diaphragm and supporting it at such a fixed distance from said rotor that it can be moved out of contact therewith by being buckled, a spring influenced lever for buckling the diaphragm and maintaining it in its buckled condition, means for actuating said lever for permitting the diaphragm to assume a condition in which 95 it will make contact with the rotor to sound a signal and means whereby the predetermined speed of the continuously driven rotor is maintained unchanged when the diaphragm makes contact therewith so that a sound of constant pitch will be emitted at each signal. 100

5. An audible code signalling device consisting in the combination of a vibratory sound emitting diaphragm, a rotor adapted to vibrate said diaphragm, a motor for driving said rotor continuously at a predetermined speed, means engaging with the periphery of said diaphragm and supporting it at such a fixed distance from said rotor that it can be moved out of contact therewith by being buckled, a diaphragm actuating lever, a spring adapted to co-operate with said lever and cause it to buckle the diaphragm and maintain it in its buckled condition, 110 electrical means for actuating said lever and permitting the diaphragm to assume a condition in which it will make contact with the rotor to sound a signal, and means whereby the predetermined speed of the continuously driven rotor is maintained unchanged 115 when the diaphragm makes contact therewith so that a sound of constant pitch will be emitted at each signal. 120

6. An audible code signalling device consisting in the combination of a vibratory sound emitting diaphragm, a rotor adapted to vibrate said diaphragm, a motor for driving said rotor continuously at a predetermined speed, means engaging with the 125

- periphery of said diaphragm and supporting it at such a fixed distance from said rotor that it can be moved out of contact therewith by being buckled, a diaphragm 5 actuating lever, a spring adapted to co-operate with said lever and cause it to buckle the diaphragm and maintain it in its buckled condition, an electro-magnet forming part of an electric circuit and adapted 10 to actuate said lever against the action of said spring to enable the diaphragm to assume a condition in which it will make contact with the rotor to sound a signal, a switch for opening and closing said circuit, and means whereby the predetermined speed of the continuously driven rotor is maintained unchanged when 45 the diaphragm makes contact therewith so that a sound of constant pitch will be emitted at each signal.
- 15 8. An audible code signalling device consisting in the combination of a vibratory sound emitting diaphragm, a rotor adapted to vibrate said diaphragm, a motor for driving said rotor continuously at a predetermined speed, means engaging with the periphery of said diaphragm and supporting it at such a fixed distance from said rotor that it can be moved out of contact therewith by being buckled, a diaphragm 20 actuating lever, stops for limiting the movement of said lever, a spring adapted to co-operate with said lever and cause it to buckle the diaphragm and maintain it in its buckled condition, an electro-magnet forming part of an electric circuit, a core piece 25 forming part of said electro-magnet and adapted to be operated manually when the circuit is open to actuate said lever against the action of said spring and enable the diaphragm to assume a condition in which it will make contact with the rotor to 30 sound a signal, a switch for opening and closing said circuit, and means whereby the predetermined speed of the continuously driven rotor is maintained unchanged when 35 the diaphragm makes contact therewith so that a sound of constant pitch will be emitted at each signal.
- 35 7. An audible code signalling device consisting in the combination of a vibratory sound emitting diaphragm, a rotor adapted to vibrate said diaphragm, a motor for driving said rotor continuously at a predetermined speed, means engaging with the periphery of said diaphragm and supporting it at such a fixed distance from said rotor that it can be moved out of contact therewith by being buckled, a diaphragm 40 actuating lever, a spring adapted to co-operate with said lever and cause it to buckle the diaphragm and maintain it in its buckled condition, an electro-magnet forming part of an electric circuit, a core piece forming part of said electro-magnet and adapted to be operated manually when the circuit is open to actuate said lever against the action of said spring and enable the diaphragm to assume a condition in

which it will make contact with the rotor to sound a signal, a switch for opening and closing said circuit, and means whereby the predetermined speed of the continuously driven rotor is maintained unchanged when 45 the diaphragm makes contact therewith so that a sound of constant pitch will be emitted at each signal.

8. An audible code signalling device consisting in the combination of a vibratory sound emitting diaphragm, a rotor adapted to vibrate said diaphragm, a motor for driving said rotor continuously at a predetermined speed, means engaging with the periphery of said diaphragm and supporting it at such a fixed distance from said rotor that it can be moved out of contact therewith by being buckled, a diaphragm actuating lever, stops for limiting the movement of said lever, a spring adapted to 60 co-operate with said lever and cause it to buckle the diaphragm and maintain it in its buckled condition, an electro-magnet, a core piece forming part of said electro-magnet 65 and adapted to be operated manually when the circuit is open to actuate said lever against the action of said spring and enable the diaphragm to assume a condition in which it will make contact with the rotor to 70 sound a signal, a switch for opening and closing said circuit, and means whereby the predetermined speed of the continuously driven rotor is maintained unchanged when 75 the diaphragm makes contact therewith so that a sound of constant pitch will be emitted at each signal.

JOHN FERREOL MONNOT,
EDWARD TINDALL COOK.
